UNITED STATES PATENT OFFICE.

SYLVESTER L. KING AND LEROY J. KING, OF ST. PAUL, MINNESOTA.

MAIL-BAG-DELIVERING DEVICE FOR RAILWAY CARS.

Application filed January 25, 1923. Serial No. 614,822.

To all whom it may concern:

Be it known that we, SYLVESTER L. KING and LEROY J. KING, citizens of the United States, residing at St. Paul, in the county of 5 Ramsey and State of Minnesota, have invented certain new and useful Improvements in Mail-Bag-Delivering Devices for Railway Cars, of which the following is a specification.

10 Our invention relates to devices for dropping or delivering mail pouches from railway cars in motion, and the object is to provide an improved device of said kind.

In the accompanying drawings—

15 Fig. 1 is a cross section of a mail car equipped with our device and showing also a device on the ground for receiving the mail pouches.

Fig. 2 is an enlarged section on the line 20 2—2 in Fig. 1.

Fig. 3 is a section on the line 3—3 in Fig. 1 showing also two hooks, one for holding the device in idle position and another for bracing the device in the middle of the car 25 door in operative position.

Fig. 4 is an enlarged section on the line 20 4—4 in Fig. 1.

Fig. 5 is a left hand end view of Fig. 6 and Fig. 6 is an enlarged portion of Fig. 1.

30 Referring to the drawing by reference numerals, 7 designates a mail car having wheels 8 on track rails 9, and near said track is fixed, on a platform 10, a frame 11 holding a smooth curved sheet 12 of such 35 length as may insure receiving a mail bag dropped from a running car.

The receiver 12 may be made of sheet metal or wood, smooth at the top and formed with an incline 12^a, a curve 12^b and a guard 40 12^c so that when a mail bag 13 is dropped from a tiltable support 14 comprising a shallow tray carried by the car it drops upon the incline 12^a where its downward sliding motion prevents a hard blow to it and as it 45 moves into the curve 12^b and partly up the inclined guard 12^c it is lodged in the position 13^a in a comparatively easy manner without damage to its contents.

Fixed upon the platform 10 or to frame 50 11, or to both, is a post 15, which when the mail car 7 passes the platform contacts with and operates the mail carrying device, which will now be described.

The car 7 usually has two opposite door 55 openings 16, 16^a. Above said openings we fix across the car a track 17 which is pref-

erably a pipe of suitable diameter for strength. Above each end of the track 17 is fixed a fork 18 (see Fig. 2). 19 is a carriage having supporting wheels 20 riding on the track 17 and at the ends of the track enters into either one of the forks 18 so as to hold the carriage from tilting sidewise on the single rail 17.

Slidably journaled in the carriage is the 60 vertical stem 21 of a horizontally disposed frame 22. Said stem has two diametrically opposite pins or projections 23 arranged to engage in notches 24 in the carriage and thereby hold the frame 22 in 65 transverse direction of the mail car and in the middle of one of the door openings to be used for delivering a mail bag as the car is in motion.

Journaled in the frame 22 is a horizontal 70 shaft 25, having fixed on its outer end the plate 14 supporting the mail bag 13, and adjacent thereto it has a radial downward arm 26 with a pin 27 engaging in a slot 28 of a beam lever 29 which is fulcrumed at 75 30 on an arm 31 depending from the frame 22. The lower arm of said beam lever is arranged to contact with the post 15 and thus automatically cause the support 14 to tilt and drop the mail bag on the receiver 12. 80

The inner end of the shaft 22 has a hand 85 lever 32 carrying a finger operated lever 33, connected with a dog 34, arranged to normally engage in a shallow notch 35 in an enlargement 36 of the inner end of the frame 90 22 (see Figs. 5 and 6).

In Fig. 5, 37 indicates a spring holding the dog 34 in the notch 35 with sufficient pressure to prevent accidental disengagement, but the spring will yield and let the dog escape the instant the rocker arm 26 (in Figs. 1 and 4) is actuated by beam lever 29 and obstruction post 15. If the car is running at a high speed the operator may facilitate the rocking of the shaft 25 by releasing the dog from the notch by the finger lever 33 and letting it rest upon the enlargement 36 ready to move further away from the notch when the post 15 is hit.

In some cases the operator may also drop 100 the mail bag by operating hand lever 32 regardless of the post 15 and the automatic means actuated by the post.

When the device is to deliver a mail bag 110 from the opposite door, 16^a, the stem 21 is pushed upward and given half a turn and let down again with the pins 23 each into a

notch 24 opposite from the notch previously occupied. This leaves the device in the dotted line position 22 in Fig. 1, ready to be projected through the door opening 16^a. 38⁵ and 38^a are braces pivoted at 39 and formed each with a double hook 40 (see Fig. 3) adapted to engage over the frame 22 and hold it steady against the strain caused by the post 15.

10 When the device is idle it may be turned on its track 17 to the horizontal position shown in Fig. 3 and supported by a hook 41 hanging from the roof 42 of the car.

It is obvious that a mail receiving device 15 similar to that marked 10—11—12 may be placed any desired distance from a passenger depot and at either side of the track.

What we claim is—

1. In a device of the class described, 20 means for receiving a mail bag from a moving mail car, and means on the car for carrying the mail bag, said carrying means comprising a track fixed across the interior of

the car above the opposite door openings thereof, wheels running on said track, a carriage suspended from the wheels, a mechanism frame having an upright shaft journaled in the carriage, a horizontally disposed shaft journaled in the mechanism frame and having at one end a tray on which to lay a mail bag, and means for partly rotating the latter shaft when the tray is outside of and in spaced relation to the side of the car, so as to cause the mail bag to drop from the tray, said tray when in operative position being tiltable in a direction parallel to the side of the car.

2. The structure specified in claim 1, and means for locking the rotatable stem of the carriage when the mail carrying shaft is 40 directed in either one of two opposite directions.

In testimony whereof we affix our signatures.

SYLVESTER L. KING.
LEROY J. KING.
